UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,387,110.

Specification of Letters Patent. Patented Aug. 9, 1921.

Application filed January 16, 1920. Serial No. 351,785.

To all whom it may concern:

Be it known that I, FRED S. CARR, a citizen of the United States, and a resident of Newton, in the county of Middlesex, Commonwealth of Massachusetts, have invented 5 an Improvement in Fasteners, of which the following description, in connection with the accompanying drawings, is a specification, like characters on the drawings representing like parts.

This invention pertains to improvements in fasteners of the stud and socket type. It is among the objects of the invention to provide a fastener having superior capacity to 15 withstand, without undesired separation of stud and socket, forces likely to result from lateral strains.

In the drawings, which show a preferred form of one embodiment of my invention:—

20 Figure 1 is a view showing two pieces of fabric secured together by a fastener shown in dotted lines;

Fig. 2 is a section on the line 2—2 of Fig. 1;

25 Fig. 3 shows two pieces of material secured together by a plurality of such fasteners;

Fig. 4 is a view of the socket shown in Fig. 2 taken from the side thereof where 30 the stud enters; and

Fig. 5 is a view of the stud.

Referring to the drawings, and to the preferred form of my invention illustrated, I have provided a fastener including a stud 6 having a head and a neck coöoperating with a socket including a casing 7 containing spring means 8. The casing preferably, as shown, comprises a disk portion having an aperture therethrough into which the head 15 of the stud can be passed for engagement with the spring jaw means and a flanged-over rim for holding the spring in the socket. The aperture through the face of the socket is preferably somewhat larger than the greatest diameter of the head of the stud, and the spring is preferably made to provide relatively abrupt curved portions intersecting at a plurality of points the aperture through the casing so that the neck 20 of the stud will be engaged by a plurality of such points or curved portions. The distance between adjacent curved portions is preferably such that when subjected to lateral strain the stud may shift somewhat to enter into 25 semi-locked relationship to the spring, the

parts being preferably so proportioned, however, that the stud can shift sufficiently to get into a position where it cannot be readily separated from the socket by force exerted at a greater angle to the line of lateral strain than is likely to be produced as a resultant of forces arising from lateral strain. To prevent an undue strain on the spring portions and to insure against too great yielding of the same which might permit separation of stud and socket under lateral strain, I preferably support the spring points or curves adjacent the aperture in the socket and I may conveniently do this by throwing up, back of each point 60 or curve, supporting portions 9 of the metal adjacent the edge of the aperture in the socket. These supporting portions are preferably so located that the spring can only yield to a point where the neck of the stud 70 will become wedged under lateral strain between the points of the spring. Sufficient play is preferably provided so that, when the stud is pulled in any given direction, the 75 spring points on the opposite side of the socket may follow the stud and remain in supporting relation thereto.

The socket is preferably made reversible, so that the stud may be entered from either side thereof. In such case the holding power 80 of the fastener against separation under lateral strain may be substantially the same whether the stud be entered from one side or the other. This will ordinarily be the case where the spring portions are central. If it 85 is desired to provide a somewhat greater holding power when the stud is entered from one side than when the stud is entered from the other side, then the spring may be located somewhat out of a plane passing through the center of the casing, in which case the holding power will be greater where the stud is entered from the side where the spring is 90 near the base of the face of the socket than when the stud is entered from the opposite side.

While I have shown and described a preferred form of one embodiment of my invention, it will be understood that changes involving omission, substitution, alteration and 105 reversal of parts, and even changes in the mode of operation, may be made without departing from the scope of my invention, which is best defined in the following claims.

1. A separable fastener comprising, in combination, a stud having a head and a neck, a socket including a spring providing a plurality of points adapted to engage the stud and having between them an opening into which the neck of the stud may be drawn, the spring portions at opposite sides of said opening being adapted to wedge the stud to oppose separation of stud and socket under forces resultant from lateral strains on stud and socket, said spring portions being back-supported by adjacent projections from the socket to limit the amount which they can yield under strain.
15. 2. A stud and socket fastener comprising, in combination, a stud having a head and a neck, and a socket comprising a casing, a spring somewhat loosely fitting said casing and permitting a limited amount of shifting of said spring in said casing, means on said casing back-supporting the spring portions engaging said stud and limiting resilient yielding thereof under strain, said parts organized and operating to wedge the stud between adjacent spring portions when strain is exerted laterally on stud and socket and

resiliently to support that side of the stud away from the portion thereof which is wedged under any given strain.

3. A separable fastener comprising, in combination, a stud having a head and a neck, a socket having a plate providing an aperture therethrough, a spring providing a plurality of stud-engaging points intersecting said aperture and spring-supporting elements projecting from said casing adjacent said aperture.

35. 4. A separable fastener comprising, in combination, a stud having a head and a neck, and a socket including a casing having an aperture therein and a plurality of spring points intersecting said aperture for engagement with the neck of the stud, said spring points being spaced apart a distance less than the diameter of the stud and back-supported to prevent separation thereof a distance equal to the diameter of the coöperating portion of the neck of said stud.

In testimony whereof, I have signed my name to this specification.

FRED S. CARR.
